BUBBLE CAP

Henry N. La Croix, Newark, N. J., assignor to
Foster Wheeler Corporation, New York, N. Y.,
a corporation of New York

Application June 22, 1948, Serial No. 34,415

8 Claims. (Cl. 261—114)

1

This invention relates to vapor and liquid contact devices and more particularly pertains to bubble caps and the association of said caps with bubble trays.

The invention provides a bubble cap comprising a plurality of openings having closure means associated therewith through which openings vapor under pressure flows into contact with liquid on a bubble tray. The closure means is actuated to open or close the openings in response to the flow of said vapor. When the closure means is open in respect to the openings, vapor is permitted to flow through the openings and into contact with liquid on the bubble tray, the pressure of the vapor preventing the flow of said liquid into the cap. Upon a decrease of the flow of the vapor below a predetermined amount, the closure means closes the openings preventing the flow of liquid through the openings.

This invention is particularly well adapted to the absorption, fractional distillation and rectification of composite liquids such as petroleum, chemicals and animal and vegetable oils, although it is useful generally to provide intimate contact of vapor and gases with liquid.

The invention will be understood from the description when considered in connection with the accompanying drawing forming a part thereof and in which:

Fig. 1 is an elevational view partly in section of one form of bubble cap embodying the invention;

Fig. 2 is a horizontal sectional view taken on the line 2—2 of Fig. 1;

Fig. 3 is an elevational view of the flow control means of the present invention prior to the positioning of said means on a bubble cap;

Fig. 4 is a transverse sectional view of a bubble cap of the present invention with the closure means opened to permit the flow of vapor from within the cap;

Fig. 5 is a horizontal, sectional view of a part of the cap shown in Fig. 4 and taken on the line 5—5 of Fig. 4, and

Fig. 6 is a view similar to Fig. 4 but of another embodiment of the invention.

Like characters of reference refer to like parts throughout the several views.

Referring to the drawing, reference character 10 designates a bubble tray arranged to hold liquid and to be disposed, for example, one above the other in vertical alignment within a fractionating column in which vapor and liquid contact is effected. As shown, the tray 10 has a plurality of spaced circular openings 11 therethrough arranged in any desired pattern.

2

An inverted, cup-shaped bubble cap 12 is positioned over each of the openings 11, the rim 13 of each cup being of such circumference that the openings are enclosed by the bubble caps. The rims 13 of the caps are secured in a fluid-tight manner, such as by welding 14 to the upper surface of tray 10. Skirt 15 of each of the bubble caps 12 has a plurality of relatively closely spaced, parallel, narrow, rectangular-shaped slots 16 arranged in a row circumferentially of the skirt with the elongated sides of said slots projecting vertically of the skirt.

Flow of fluid, either liquid or vapor, through each of the slots is individually controlled by control means. As shown, the control means comprises a flat strip 18 of relatively thin flexible material in which is formed a plurality of spaced flexible reeds 17 that are the same shape as slots 16 in the bubble cap skirt and of such larger size that the reed will completely close a slot 16 as will hereinafter be fully described. For example, when the slots are rectangular-shaped, as shown in the drawings, the elongated sides of the reeds 17 will be of greater length than the elongated sides of the slot 16 and will be spaced from one another a greater distance than the elongated sides of said slots are spaced from one another. Reeds 17 are formed within the flexible strip 18 by cutting said strip to form elongated sides 19 and 20 and the end 21 of each of reeds 17. The opposite surfaces of reeds 17 are normally in the same plane as the corresponding surface of the remainder of strip 18 the reeds being movable away from strip 18 against the tension of the material of the strip, pivoting at the end 22 opposite end 21 of said reed and moved on a pivot line toward the strip by the tension of said material.

Strip 18 is positioned on the skirt 15 of bubble cap 12 so that each of the reeds 17 covers a slot 16 in said skirt, the strip thereafter being secured in position on skirt 15 by welding or otherwise. Reeds 17 bear against the outer peripheral surface of the skirt 15 of bubble cap 12 adjacent both of the elongated sides of the slots and both of the opposite ends of said slots.

In operation, vapor under pressure, for example, vapor passing upwardly through a fractionating tower, flows through circular openings 11 in bubble tray 10 and into the fluid-tight chamber within bubble caps 12. Flow of vapor within caps 12 causes the flexible reeds 17 to bend outwardly under tension along the pivot line at the end 22 of each of said reeds. Flexing outwardly of the reeds 17, opens slots 16 permitting vapor to flow therethrough and bubble upwardly through liquid on the tray which liquid normally is at a level

slightly higher than the upper end of slots 16, as shown in Figs. 1 and 4. It will be understood that the greater the amount of flow within the caps 12 the greater will be the amount of movement of reeds 17 outwardly from the skirt of the caps. When the flow within the caps 12 decreases, the reeds 17 will be moved inwardly toward the skirt of said caps by the tension of the strip 18. When the flow within the caps 12 is such that it is insufficient to move the reeds 17 outwardly and away from the skirt of said caps against the tension of the material of which strip 18 is composed, the surface of the reeds 17 adjacent the outer peripheral surface of the skirt 15 of the caps 12 will bear against said outer peripheral surface of the skirts adjacent the periphery of the slots 16. Pressure of the liquid on the tray 11 will cause the reeds to be maintained in engagement with the outer peripheral surface of the skirt of the caps thus preventing liquid on said tray from passing through slots 16 into caps 12 and thence through openings 11.

The embodiment of the invention disclosed in Fig. 6 is somewhat similar to the form illustrated in Figs. 1 to 5 with the exception that the strip 18 is so positioned on the skirt 15 of caps 12 that the end 21 of reeds 17 is adjacent the upper end of slots 16 so that the reeds will flex outwardly along the pivot line 22 which is located adjacent the bottom of a slot 16 thereby opening said slots from a point adjacent the bottom thereof toward the top thereof. The opening in the form of the invention shown in Fig. 6, therefore, is from the top of slots 16 rather than from the bottom as in the embodiment of the invention disclosed in Figs. 1 to 4.

With the present invention, risers are omitted and the required circumferential space between the outer periphery of the riser and the inner periphery of a bubble cap of the conventional design of bubble cap and tray is likewise omitted thereby permitting the use of bubble caps of smaller diameter in relationship to the diameter of the riser than is possible with conventional designs. This results in a considerable saving of tray area making possible the use of towers of smaller diameter and providing a more intimate contact of vapor with liquid throughout the area of the tray. Also, accurate leveling of bubble caps upon a tray to insure an even flow of vapor from the slots of all of the caps as is required with the conventional bubble caps, is not necessary with the cap of the present invention. With the device of the present invention, the reeds are self-adjusting to the volume of vapor passing through the slots of a cap and insure the proper contact of vapor and liquid even when the depth of liquid on a tray is low.

The invention is applicable to bubble caps of shapes other than those illustrated, such as rectangular, oval, or any multi-sided shape.

The term "vapor" as used herein and in the claims includes "gas."

It will be understood that changes may be made in the forms of the invention disclosed without departing from the principles of the invention which is not to be limited excepting by the scope of the appended claims.

What is claimed is:

1. A bubble tray comprising a liquid holding portion with a plurality of openings therethrough, a bubble cap positioned over each of said openings, the cap having a skirt portion normally submerged in liquid on the tray and provided with a plurality of elongated vapor passages there-

through with the longer walls of the passages extending substantially axially of the cap, the passages being arranged parallel to and spaced from one another in a row extending circumferentially of the cap, said vapor passages having spaced opposite elongated sides and spaced opposite ends, and vapor flow controlling means comprising a band of flexible material extending around said skirt of a cap and mounted thereon, the band having a plurality of individual vapor passage controlling members, each one of said members being formed in the band adjacent one of said vapor passages and having a surface thereof which abuts the peripheral surface of the skirt around a passage in a fluid-tight manner, the members having opposite sides and opposite ends adjacent the opposite sides and opposite ends of the vapor passages but spaced apart a greater distance than said sides and ends of the passages so that the members will close said passages, the vapor flow controlling members being so mounted in respect to the cap that one end is fixed in relationship to the cap and the remainder of the member is movable outwardly from the passage with which it is associated against the tension of said material, the construction and arrangement being such that vapor flow above a predetermined amount within the cap pivots said members on said fixed end thereof to an opened position with respect to the vapor passages with which they individually are associated and tension of said flexible members pivots the members on said fixed end to a closed position with respect to the passages with which they individually are associated upon the decrease of said flow to a predetermined amount.

2. A bubble tray comprising a liquid holding portion with a plurality of openings therethrough, a cup-shaped bubble cap positioned over each of said openings in a fluid-tight manner, the cap having a skirt portion normally submerged in liquid on the tray and provided with a plurality of elongated substantially rectangular shaped vapor passages therethrough with the longer walls of the passages extending axially of the cap, the passages being arranged parallel to and spaced from one another in a row extending circumferentially of the cap, and vapor flow controlling means comprising a band of flexible material extending around said skirt of a cap and mounted thereon, the band having a plurality of individual vapor passage controlling members, each one of said members being formed in the band adjacent one of said vapor passages and having a surface thereof which abuts the peripheral surface of the skirt around a passage in a fluid-tight manner, the members having opposite sides and opposite ends adjacent the opposite sides and opposite ends of the vapor passages but spaced apart a greater distance than said sides and ends of the passages so that the members will close said passages, the vapor flow controlling members being so mounted in respect to the cap that one end is fixed in relationship to the cap and the remainder of the member is movable outwardly from the passage with which it is associated against the tension of said material, the construction and arrangement being such that vapor flow above a predetermined amount within the cap pivots said members on said fixed end thereof to an opened position with respect to the vapor passages with which they individually are associated and tension of said flexible members pivots the members on said fixed end to a closed position with respect to the passages with which

they individually are associated upon the decrease of said flow to a predetermined amount.

3. Vapor and liquid contact apparatus comprising a tray having a liquid holding portion with a plurality of openings therethrough, a cap positioned over each of the openings and extending into said liquid holding portion of the tray, the cap having a portion normally submerged in the liquid on the tray and provided with a plurality of separate vapor passages, flow controlling means comprising a band of flexible material extending around the portion normally submerged in the liquid and mounted thereon, and a plurality of flexible reeds formed in said band, the reeds being attached along a portion thereof to the band and normally engaging said submerged portion of the cap in a fluid-tight manner, said reeds being free to flex outwardly from the band on said portion, each reed being disposed in alignment with a vapor passage and of a dimension to cover said passage in a fluid-tight manner when the reed is in said normal position, the reeds being adapted to be flexed outwardly from its normal position to open said passage by flow of vapor within the cap.

4. Vapor and liquid contact apparatus comprising a tray having a liquid holding portion with a plurality of openings therethrough, a cap positioned over each of the openings and extending into said liquid holding portion of the tray, the cap having a portion normally submerged in the liquid on the tray and provided with a plurality of separate vapor passages, flow controlling means comprising a band of flexible material extending around the portion normally submerged in the liquid and mounted thereon, and a plurality of flexible reeds formed in said band, the reeds being attached along a portion thereof to the band and normally engaging said submerged portion of the cap in a fluid-tight manner, said reeds being free to flex outwardly from the band on said portion, each reed being disposed in alignment with a vapor passage and of a dimension to cover said passage in a fluid-tight manner when the reed is in said normal position, the reeds being adapted to close said passage in a fluid-tight manner when the flow of vapor within the cap is less than a predetermined amount and to be flexed outwardly to an open position against the tension of said flexible material upon an increase of vapor flow within the cap above a predetermined amount.

5. Vapor and liquid contact apparatus comprising a tray having a liquid holding portion with a plurality of openings therethrough, a cap positioned over each of the openings and extending into said liquid holding portion of the tray, the cap having a portion normally submerged in the liquid on the tray and provided with a plurality of separate vapor passages, flow controlling means comprising a band of flexible material extending around the portion normally submerged in the liquid and mounted thereon, and a plurality of flexible reeds formed in said band, the reeds being attached along a portion thereof to the band and normally engaging said submerged portion of the cap in a fluid-tight manner, said reeds being free to flex outwardly from the band on said portion, each reed being of substantially the same shape as and disposed in alignment with a vapor passage, each reed also being of a dimension to cover said passage in a fluid-tight manner when the reed is in said normal position and to be flexed outwardly

to open said passage by flow of vapor within the cap.

6. A bubble tray comprising a liquid holding portion with a plurality of openings therethrough, a bubble cap positioned over each of said openings in a fluid-tight manner, the cap having a skirt portion normally submerged in liquid on the tray and provided with a plurality of elongated vapor passages therethrough with the longer walls of the passages extending substantially axially of the cap, the passages being arranged parallel to and spaced from one another in a row extending circumferentially of the cap, said vapor passages having spaced opposite elongated sides and spaced opposite ends, flow controlling means comprising a band of flexible material extending around the portion normally submerged in the liquid and mounted thereon, a plurality of flexible reeds formed in said band, each of said reeds being associated with a vapor passage and of substantially the same shape as said passage, the reeds having opposite sides and opposite ends adjacent the opposite sides and opposite ends of the vapor passages but spaced apart a greater distance than said sides and ends of the passages so that the reeds will close said passages in a fluid-tight manner when in their normal position, the reeds being attached to the band at one end only thereof and the remainder of the reed being movable outwardly from the passage with which it is associated against the tension of said material to open said passage by flow of vapor within the cap.

7. A bubble tray comprising a liquid holding portion with a plurality of openings therethrough, a bubble cap positioned over each of said openings in a fluid-tight manner, the cap having a skirt portion normally submerged in liquid on the tray and provided with a plurality of elongated vapor passages therethrough with the longer walls of the passages extending substantially axially of the cap, the passages being arranged parallel to and spaced from one another in a row extending circumferentially of the cap, said vapor passages having spaced opposite elongated sides and spaced opposite ends, flow controlling means comprising a band of flexible material extending around the portion normally submerged in the liquid and mounted thereon, and a plurality of flexible reeds formed in said band, each of said reeds being associated with a vapor passage and of substantially the same shape as said passage, the reeds having opposite sides and opposite ends adjacent the opposite sides and opposite ends of the vapor passages but spaced apart a greater distance than said sides and ends of the passages so that the reeds will close said passages in a fluid-tight manner when in their normal position, the reeds being attached to the band at the lower end only thereof and the remainder of the reed being movable outwardly from the passage with which it is associated against the tension of said material, the construction and arrangement being such that vapor flow above a predetermined amount within the cap flexes the reeds on said attached end thereof to an opened position with respect to the vapor passages with which they individually are associated and tension of said flexible material pivots the reeds on said attached end to a closed position with respect to the passages with which they individually are associated upon the decrease of said flow to a predetermined amount.

portion with a plurality of openings therethrough, a bubble cap positioned over each of said openings in a fluid-tight manner, the cap having a skirt portion normally submerged in liquid on the tray and provided with a plurality of elongated vapor passages therethrough with the longer walls of the passages extending substantially axially of the cap, the passages being arranged parallel to and spaced from one another in a row extending circumferentially of the cap, said vapor passages having spaced opposite elongated sides and spaced opposite ends, flow controlling means comprising a band of flexible material extending around the portion normally submerged in the liquid and mounted thereon, and a plurality of flexible reeds formed in said band, each of said reeds being associated with a vapor passage and of substantially the same shape as said passage, the reeds having opposite sides and opposite ends adjacent the opposite sides and opposite ends of the vapor passages but spaced apart a greater distance than said sides and ends of the passages so that the reeds will close said passages in a fluid-tight manner when in their normal position, the reeds being attached to the band at the upper end only thereof and the remainder of the reed being movable out-
